UNITED STATES PATENT OFFICE.

EDWARD F. DUFFY, OF HARTFORD, CONNECTICUT.

HYDRANT.

SPECIFICATION forming part of Letters Patent No. 618,169, dated January 24, 1899.

Application filed June 22, 1898. Serial No. 684,131. (No model.)

To all whom it may concern:

Be it known that I, EDWARD F. DUFFY, a citizen of the United States of America, residing at Hartford, in the county of Hartford and State of Connecticut, have invented a certain new and useful Improvement in Hydrants, of which the following is a description, reference being had to the accompanying drawings, wherein—

10 Figure 1 is a view in central vertical longitudinal section with the main valve of the hydrant closed. Fig. 2 is a view in horizontal cross-section on the plane denoted by the dotted line $\alpha\alpha$ appurtenant to Fig. 1.

15 The improvements herein described and claimed appertain to hydrants.

In the accompanying drawings the letters a , b , and c , respectively, denote sections of the hydrant-case, which is made up of these parts 20 collectively. Through the lower section c there is an inlet-orifice d for admitting water to the hydrant from the street-main. The letter e denotes the valve appurtenant to that 25 inlet-orifice. Its face or front is on an incline, and the valve-seat f is correspondingly inclined. The rear side of the valve e is also inclined, so that the valve as a whole is wedge-shaped. The letter g denotes a shoe correspondingly inclined upon its face, and thereby 30 adapted to coöperate with the rear side of the valve.

The letter h denotes the "valve-rod," by which expression is meant the rod by which the valve is operated. Near its lower part it has 35 two different screw-threads, one of them running in one direction and the other running in an opposite direction. The lower of these two screw-threads upon the valve takes into and through valve e . The upper of these two 40 screw-threads takes into and through the lateral part of the shoe g . Obviously it results from this construction that the valve e and shoe g are both supported by and on the valve-rod h . It is by rotation of this valve-rod that 45 the valve e is moved to close and unclose the

inlet-orifice d . By reason of the wedge shape of the valve e and the corresponding inclines of the valve-seat f and the shoe g , the valve is pressed the more snugly to its seat the farther it is moved upward. By having the valve 50 and the shoe hung upon the two different screw-threads, this closing action of the valve is accelerated.

The valve-rod is adapted to be operated by a wrench at the top of the hydrant-case. 55 Near the top of the hydrant-case the valve-rod is held from longitudinal motion, but permitted to rotate.

The hydrant is provided with a drip-valve which is closed by a spring of sufficient force 60 whenever the main valve of the hydrant is open, but which is opened in order to empty the hydrant-case of water whenever the main valve is closed. The letter i denotes this drip-valve borne on the pintle k and pressed to 65 its seat normally by the spring l . When the main valve of the hydrant e is closed, the shoe g bears against the valve-pintle k , holding the drip-valve open and permitting the water which would otherwise be confined within the 70 hydrant-case to escape but when the main valve e of the hydrant is open the shoe g fails to press upon the valve-pintle k , with the result that at such times the drip-valve remains shut. 75

I claim as my improvement—

In combination, the hydrant-case, the inlet-orifice, the wedge-shaped valve, the inclined valve-seat, the shoe at the rear of the valve with inclined face, and the screw-rod taking 80 on it the valve by a screw-thread running in one direction, and also taking said shoe upon it by a screw-thread running in the opposite direction, all substantially as described and for the purposes set forth.

EDWARD F. DUFFY.
